WITNESS

A diagram showing a rectangular component with a central slot. Reference numeral 16 points to the left end, 17 points to the right end, 13 points to the top right corner, and 18 points to the bottom right corner.

INVENTOR.
Charles B. Ulrich:
BY Albert C. Bell
ATTORNEY

UNITED STATES PATENT OFFICE.

CHARLES B. ULRICH, OF JAMESTOWN, NEW YORK.

FILING-CABINET.

1,306,728.

Specification of Letters Patent. Patented June 17, 1919.

Application filed July 25, 1917. Serial No. 182,764.

To all whom it may concern:

Be it known that I, CHARLES B. ULRICH, a citizen of the United States, residing at Jamestown, in the county of Chautauqua and State of New York, have invented an Improved Filing-Cabinet, of which the following is a specification, reference being had to the accompanying drawings, forming a part thereof.

10 My invention relates to an improved construction of filing cabinet in which a casing is formed of a sufficient size to receive a single filing drawer or other detail construction forming a part of the entire filing system so

15 that the cabinet constitutes a unit of such construction that a plurality of the units may be stacked one on the other and a plurality of stacks may be employed depending upon the capacity which the filing system must have.

By my invention I provide the top and bottom of the unit cabinet with a groove or grooves extending longitudinally of the cabinet, these grooves opening in the same direction and being similarly conformed so that when two or more of the units are stacked upon each other the walls of the grooves engage each other to prevent lateral displacement of one unit relatively to the others in the same stack. I also preferably provide one or more of the grooves at its end with a projecting tongue for engaging the adjacent unit cabinet in a stack to prevent vertical separation of the units. This is particularly desirable when the drawers are somewhat heavily loaded to prevent the unit tilting toward the operator when the drawers are pulled out. The grooves referred to are formed preferably by making the top and bottom of the unit cabinet of sheet metal having formed flanges extending downwardly from the top and bottom, these flanges serving to reinforce and stiffen the top and bottom and the top flanges serving as slides for engaging the upper edge of the rear end of the drawer contained in a unit when the drawer is pulled out so that its center of gravity is outside of the unit casing. By my invention I also provide an improved anti-friction device in the front end of the unit cabinet to constitute a bearing for the under surface of the drawer as it is moved into and out of the cabinet.

It is customary in making metal filing devices of this kind to form both the drawer and cabinet from thin sheet iron or steel, the ends of the cabinet being usually reinforced in one manner or another by bars of iron or steel. The use of other metals for this purpose is prohibitive on account of their cost and it has been found that the rolled iron or steel parts usually employed develop a relatively large amount of friction on account of the tendency of the metals to cut or drag when rubbed upon each other. By my invention I provide a bearing plate of brass or other metal having relatively small friction in connection with iron or steel so that the friction of the drawer sliding on the front end of the cabinet is reduced to a minimum.

The several drawings illustrating my invention are as follows:

Figure 1 shows a cabinet unit in transverse vertical sectional view taken along the line 1—1 in Fig. 2.

Fig. 2 is a longitudinal vertical sectional view through the parts shown in Fig. 1 taken along the line 2—2,

Fig. 3 shows in plan view the lower portion of the front end of a cabinet unit, the remaining portion of the unit being broken away,

Fig. 4 is a front end view of the cabinet unit shown in Fig. 2, the drawer contained in said unit being shown in section taken along the line 4—4,

Fig. 5 is a detailed view of the parts shown in Fig. 3 taken along the line 5—5,

Fig. 6 shows in an enlarged detail view similar to Fig. 1 one of the rollers of the drawer, and,

Fig. 7 is a detailed view showing the manner of engagement between the bottom of one cabinet unit and the top of another cabinet unit when placed upon each other in a stack.

Similar numerals refer to similar parts throughout the several views.

As shown in Figs. 1 and 2 the unit consists of a cabinet or casing having a top wall 10, side walls 11 and 12 and a bottom wall 13 formed preferably from thin sheet iron or steel. As indicated in Fig. 2 the front and rear ends of the unit are reinforced by bent bars 14 and 15 respectively.

The top 10 is provided with two upwardly opening grooves 16 extending from front to rear nearly the length of the unit, two similar grooves 17 being formed in the bottom 13 5 and similarly placed, the only difference being that the grooves 17 are somewhat narrower than the grooves 16 so that the outer surface of the walls of a groove 17 will fit into a groove 16 similarly located in the top 10 of another unit. As indicated in Fig. 2 the lower wall of each groove 17 is extended 10 into a tongue 18, which when two units are stacked one upon the other rests below the top 10 of the unit below it as indicated in 15 Fig. 7.

The walls of the grooves 16 and 17 constitute downwardly extending flanges which serve to reinforce and strengthen the top and bottom of the cabinet unit and as a result 20 of the conformation of the grooves described it will be observed that when one unit is stacked upon another the walls of the grooves, by their engagement, prevent lateral and longitudinal displacement of the 25 stacked units relatively to each other and that the tongues 18 prevent vertical displacement of the units relatively to each other. While I have shown two grooves 16 and two grooves 17 it will be understood that I do 30 not limit myself to any particular number of grooves in the top and bottom for the purpose described as any number which is practical or desirable for other considerations will serve to secure the interlocking relation 35 referred to. In the inner lower corners of the cabinet unit bent guideways 19 are secured to support the rear end of the drawer 20 as the latter is moved outwardly and inwardly in the unit. Rollers 21 are provided 40 at the rear end of the drawer to eliminate frictional engagement between the rear portion of the drawer and the guideways. To reduce the friction of engagement of the drawer at its front end a bearing strip 22 45 of brass or other material having a low coefficient of friction with iron or steel is placed upon the lower portion of the reinforcing bar 14, which strip preferably extends entirely across the opening in the front 50 end of the unit and is provided with rearwardly extending bent ends 23 to enter the forward ends of the space between the guideways 19 and the bottom of the unit. The bearing surface of the guideways 55 19 and the upper surface of the strip 22 are preferably substantially in the same plane. To assist in retaining the strip 22 in place lugs 24 may be bent upwardly from the bottom 13 of the unit to engage the 60 edges of the bent ends 23. The construction of the strip 22 in the manner described permits placing it in the position indicated by slightly springing the parts after which it is securely held in place without additional 65 fastening devices. While the strip 22 is

shown in the drawings as extending entirely across the open end of the unit it may be replaced by any equivalent construction providing bearing surfaces of the character referred to in line with the portions of the 70 drawer coming in frictional engagement with the lower front portion of the unit.

The rear wall of the drawer extends upwardly so that its upper edge is adjacent the inner surface of the flanges formed by 75 the grooves 16, as a result of which said flanges serve as bearing surfaces for the upper portion of the rear end of the drawer when the drawer is moved from the unit sufficiently to bring the center of gravity of 80 the drawer outside of the units. For this position of the parts the tongues 18 prevent the unit containing the extended drawer from tilting over toward the operator when said unit is stacked upon another similar 85 unit.

While I have shown my invention in the particular embodiments above described it will be understood that I do not limit myself to these exact constructions as I may 90 employ any equivalents thereof known to the art at the time of the filing of this application without departing from the scope of the appended claims.

What I claim is:

1. In a filing device, a cabinet unit having a sheet metal top and bottom provided with formed grooves extending longitudinally of said cabinet and opening in the same direction, the grooves being of a size 100 such that the walls of a groove on the bottom of one such unit engage the walls of a groove on the top of another such unit when the units are stacked one on the other to prevent horizontal displacement of said units 105 relatively to each other, said grooves extending substantially from front to rear of said cabinet to reinforce the top and bottom thereof.

2. In a filing device, a cabinet unit having 110 a sheet metal top and bottom provided with formed grooves extending longitudinally of said cabinet and opening in the same direction, the grooves being of a size such that the walls of a groove on the bottom of one 115 such unit engage the walls of a groove on the top of another such unit when the units are stacked one on the other to prevent horizontal displacement of said units relatively to each other, one of said grooves having a 120 tongue projecting from its rear end to engage the adjacent unit to prevent vertical separation of the stacked units when said walls are in engagement.

3. In a filing device, a cabinet unit having 125 a sheet metal top and bottom provided with formed grooves extending longitudinally of said cabinet and opening in the same direction, the grooves being of a size such that the walls of a groove on the bottom of one 130

- such unit engage the walls of a groove on the top of another such unit when the units are stacked one on the other to prevent horizontal displacement of said units relatively to each other, said grooves extending substantially from front to rear of said cabinet to reinforce the top and bottom thereof, one of said grooves having a tongue projecting from its rear end to engage the adjacent unit to prevent vertical separation of the stacked units when said walls are in engagement.
4. In a filing device, a cabinet unit having a sheet metal top and bottom provided with formed grooves extending longitudinally of said cabinet and opening upwardly, the grooves being of a size such that the walls of a groove on the bottom of one such unit engage the walls of a groove on the top of another such unit when the units are stacked one on the other to prevent horizontal displacement of said units relatively to each other, said grooves extending substantially from front to rear of said cabinet to reinforce the top and bottom thereof.
5. In a filing device, a cabinet unit having a sheet metal top and bottom provided with formed grooves extending longitudinally of said cabinet and opening upwardly, the grooves being of a size such that the walls of a groove on the bottom of one such unit engage the walls of a groove on the top of another such unit when the units are stacked one on the other to prevent horizontal displacement of said units relatively to each other, a groove on the bottom of a first such unit having a tongue projecting from its rear end under the top of a second such unit to prevent vertical separation of the stacked units.
6. In a filing device, a cabinet unit having a sheet metal top and bottom provided with formed grooves extending longitudinally of said cabinet and opening upwardly, the grooves being of a size such that the walls of a groove on the bottom of one such unit engage the walls of a groove on the top of another such unit when the units are stacked one on the other to prevent horizontal displacement of said units relatively to each other, said grooves extending substantially from front to rear of said cabinet to reinforce the top and bottom thereof, a groove on the bottom of a first such unit having a tongue projecting from its rear end under the top of a second such unit to prevent vertical separation of the stacked units.
7. In a filing device, a cabinet unit having a sheet metal top and bottom provided with formed grooves extending longitudinally of said cabinet and opening upwardly, the grooves being of a size such that the walls of a groove on the bottom of one such unit engage the walls of a groove on the top of another such unit when the units are stacked
- one on the other to prevent horizontal displacement of said units relatively to each other, and a drawer movable longitudinally in said unit, said drawer having a rear wall extending nearly into engagement with the bottom wall of the groove in the top of said unit, whereby said bottom wall constitutes a slide for the rear end of the drawer when the latter is moved outwardly from the cabinet unit.
8. In a filing device, a cabinet having a sheet metal top provided with an inwardly projecting formed flange extending longitudinally of said cabinet to reinforce said top, and a drawer movable longitudinally in said cabinet, said drawer having a rear wall terminating adjacent the inner surface of said flange, whereby said flange constitutes a slide for the rear end of the drawer when the latter is moved outwardly from the cabinet.
9. In a filing device, a cabinet unit having a sheet metal top and bottom each provided with a pair of formed downwardly projecting grooved flanges, said flanges being similarly formed parallel with the sides of said unit, whereby when two such units are stacked, the bottom flanges on the upper unit engage the top flanges on the bottom unit to prevent horizontal displacement of said units, each of said bottom flanges having a tongue projecting from its rear end engaging the under surface of the top of an adjacent unit when said units are stacked to prevent vertical separation of said units.
10. In a filing device, a cabinet unit having a sheet metal top and bottom each provided with a pair of formed downwardly projecting grooved flanges, said flanges being similarly formed parallel with the sides of said unit, whereby when two such units are stacked, the bottom flanges on the upper unit engage the top flanges on the bottom unit to prevent horizontal displacement of said units, and a drawer movable longitudinally in said unit, said drawer having a rear wall extending nearly into engagement with said top flanges, whereby said top flanges constitute slides for the rear end of said drawer when the latter is moved into its outer position.
11. In a file, a cabinet unit having a reinforcing bar of iron or steel around its open end, and a strip of anti-friction metal carried by the lower portion of said bar for sliding engagement with a drawer, and hollow drawer guideways carried by said unit, said strip having retaining ends extending into the ends of said guideways.
12. In a file, a cabinet unit having a reinforcing bar of iron or steel around its open end, and a strip of anti-friction metal carried by the lower portion of said bar for sliding engagement with a drawer, said strip having bent extensions engaging the rear

edge of said bar for holding said strip in place.

13. In a file, a cabinet unit having a reinforcing bar of iron or steel around its open end, and a strip of anti-friction metal carried by the lower portion of said bar for sliding engagement with a drawer, and hollow drawer guideways carried by said unit, said

strip having retaining ends extending into the ends of said guideways, said retaining ends being bent to engage the rear edge of said bar and thereby lock said strip in place.

In witness whereof, I hereunto subscribe my name this 13th day of July, A. D. 1917.

CHARLES B. ULRICH.
